US00D768299S

(12) **United States Design Patent** (10) Patent No.: **US D768,299 S**
Kim et al. (45) Date of Patent: ** Oct. 4, 2016

(54) **COMPUTER TOMOGRAPHY APPARATUS**

- (71) Applicant: **Samsung Electronics Co., Ltd.**, Suwon-si, Gyeonggi-do (KR)
- (72) Inventors: **Yun-Su Kim**, Seoul (KR); **Euisik Kim**, Seoul (KR); **Yeonmoo Chung**, Seoul (KR)
- (73) Assignee: **Samsung Electronics Co., Ltd.**, Gyeonggi-do (KR)
- (**) Term: **14 Years**
- (21) Appl. No.: **29/518,359**
- (22) Filed: **Feb. 23, 2015**

Related U.S. Application Data

- (63) Continuation of application No. 29/482,726, filed on Feb. 21, 2014, now Pat. No. Des. 726,916.

(57) **CLAIM**

The ornamental design for a computer tomography apparatus, as shown and described.

DESCRIPTION

FIG. 1 is a front perspective view of a computer tomography apparatus, showing our new design;
FIG. 2 is a front view thereof;
FIG. 3 is a rear view thereof;
FIG. 4 is a left-side view thereof;
FIG. 5 is a right-side view thereof;
FIG. 6 is a top plan view thereof; and,
FIG. 7 is a bottom plan view thereof.
The broken lines in the drawing views illustrate portions of the computer tomography apparatus that form no part of the claimed design.
